BOTTLE COVER

Herman Louis Keun, Atwater, Ohio

Application September 2, 1938, Serial No. 228,155

1 Claim. (Cl. 215—63)

This invention relates to covers and closures and particularly to removable covers or caps used on milk bottles in the home after the original seal or cap is broken.

5 An object of the invention is to provide a device of the class mentioned which is made of only two simple metal stampings easily assembled and inexpensive to manufacture.

A further object is to construct such device so 10 that it may be easily cleaned, rinsed or washed and without dirt retaining corners or recesses.

Another object of the invention is to provide a device of this class which is universal in character, that is, one which fits on all milk bottles 15 without special adjustment or construction.

A still further object is to construct a device of the character mentioned which snaps onto a bottle lip utilizing one spring for attaching the cover as well as for retaining the cover in its 20 normally closed position.

Still another object of the invention is to form the two parts of the device so that they may be nested or fitted in compact packages for economic shipping of large quantities.

25 These and other objects and features of the invention will become apparent from a reading of the following specification and claim taken together with the accompanying drawing in which like parts are designated by like reference characters and wherein:

Figure 1 is a front view of the bottle cap applied to a conventional milk bottle;

Figure 2 is a sectional side view of the same;

Figure 3 is a side view of the cover partly open;

35 Figure 4 is an enlarged view of the cover and spring to illustrate method of attaching the parts together;

Figure 5 is a sectional view of the cover and spring taken along the lines 5—5 of the Figure 4;

40 Figure 6 is a side sectional view of a modified form of cover; and

Figure 7 is a sectional view of a part of a cover showing the formation of the spring holding tongues before the spring member is inserted 45 and peened in place.

This invention consists primarily of two parts, the cover member 11 and the spring member 21.

The cover member 11 is a simple disk 12 of stamped metal which is provided with a downwardly extending thumb lever 13. The thumb lever 13 is somewhat wider at its top portion 14 to facilitate manipulation. The lever 13 also has a rectangular opening 15 which extends downwardly for approximately one-quarter of the length of the thumb lever 13 and which slot

or opening 15 starts at about where the disk portion 12 joins the said thumb lever 13.

The disk portion 12 of the cover member 11 is slightly larger than the mouth of an ordinary milk bottle. At approximately its center there is stamped or cut a small slot 16 which extends transversely of the thumb lever 13. The slot 16 is just long enough and wide enough to accommodate the special spring 21 hereinafter described in detail.

Slightly inward toward the lever 13 and in line with the slot 16 are two downwardly projecting tabs or tongues 17 for clamping or retaining the spring member 21 in place. These tongues may be stamped in the metal at the same time the cap member itself is formed. The tabs or tongues 17 are bent inward slightly so as to facilitate the nesting of the caps when they are shipped in large quantities before assembly. This is more clearly illustrated in the view of Figure 7.

20 The spring member 21 is a simple strip of steel, brass or other suitable material about three and one-half inches long and about one-quarter inch wide. Approximately four-fifths of its length is curved or somewhat spiraliform in 25 shape. The curved portion 22 is clearly indicated in the view of Figure 4. The rest of its length indicated by the character 23 is substantially straight but has a slight bend where it is clamped and held by the tongues 17.

30 The straight portion 23 of the spring member 21 is inserted in the slot 16 until the curved portion 22 meets the disk 12. The tongues 17 are then hammered down so as to firmly peen or hold the spring member 21 in the slot 16. This 35 assembly brings the opposite end 24 of the curved portion 22 through the rectangular opening 15 in the thumb lever 13. The end 25 of the straight portion 23 of the spring member is bent downward about one-quarter of an inch or just 40 enough so that it engages the inside shoulder 31 of the container 30. To attach the cover to a bottle the user simply slides the disk portion 12 across the top of the container until the spring end 24 engages the outside groove or lip 32 and 45 the end 25 snaps onto or engages the bottle inside shoulder 31. The cover 11 is held in place by the pressure or tension existing between the spring ends 24 and 25. To remove the cover, one need only to lift it or slide the spring ends 50 24 and 25 up past the mouth of the bottle.

55 The drawing of Figure 6 illustrates a modified design of cover. The modified design operates the same as the one previously described except that the disk portion 12a is somewhat con- 55

cave and has a circular flange 18 around its edge which enables it to be more closely fitted to the mouth of the bottle 30.

- As conductive to a clearer understanding of this invention it may be well to point out that there are many similar devices already patented and on the market. However, none of them embody the extreme simplicity of design shown in this invention. Because of the few parts needed and 10 because each of the two parts may be simple metal stampings, the cost of manufacture is extremely low. Furthermore, because of this fact the article lends itself to free distribution as an advertising medium or other sales stimulant.
- 15 It will now be clear that I have provided a bottle cover which accomplishes the objects of the invention. While the invention has been described in its preferred forms and while certain specific terms and language have been used, 20 it is to be understood that the embodiment of the invention as described is merely illustrative and is not to be considered in a limiting sense as various changes may be made in the mate-

rials or assembly without departing from the spirit of the invention as no limitation upon it are intended other than those imposed thereon by the scope of the appended claim.

I claim:

5 A cover for a milk bottle of the type having an internal circumferential shoulder and an external circumferential groove, comprising in combination, a cover member having a slot therein, a thumb lever having an opening therethrough, 10 the said thumb lever being integral with the said cover member, a substantially curved spring member having a straight end and a curved end, and tabs on the bottom of the cover member for retaining the spring member in fixed relation thereto and in a manner whereby the said spring member projects upward through the said slot in the cover member, and downward through the opening in the thumb lever thereby causing the straight end of the spring member to engage the bottle shoulder and the curved end to 15 engage the said bottle groove.

H. LOUIS KEUN.
